Philip S. McLean
ATTORNEY

UNITED STATES PATENT OFFICE.

DAVID CONLAN, JR., OF BROOKLYN, NEW YORK, ASSIGNOR TO HARVEY HUBBELL, INC.,
A CORPORATION OF CONNECTICUT.

ELECTRICAL APPARATUS.

Original application filed December 24, 1920, Serial No. 432,983. Divided and this application filed June 13, 1921. Serial No. 477,003.

To all whom it may concern:

Be it known that I, DAVID CONLAN, Jr., a citizen of the United States, and a resident of Brooklyn, Kings County, and State 5 of New York, have invented certain new and useful Improvements in Electrical Apparatus, of which the following is a specification.

This invention relates to circuit extension 10 devices on the order of those disclosed in Patent 1,363,394 and in my co-pending application, Serial No. 432,983, the present application being a division from the application referred to.

15 In my prior inventions, branch circuits are supplied by cords entered through the sides of special attachment plugs designed so that they may be connected end-on-end to an indefinite number.

20 One of the objects of this invention is to improve on that construction and particularly as regards the separation of the various units so as to make it possible for a pull on the extension cord or cords to effect the 25 uncoupling of the units.

Other objects are to provide a simple and practical strain relief for the outlet cord and to protect and support the angularly extending portion of the cord where it leaves 30 the side of the plug structure.

These and other objects are attained in my invention by means of certain novel features of construction, combination, arrangement and relation of parts, as will 35 appear from the following specification, which should be read in conjunction with the accompanying drawing wherein I have illustrated the invention embodied in one of its simplest and most practical forms.

40 Figure 1 in the drawing referred to is a perspective view showing several of the interchangeable plug units in separated relation and illustrating how one may be plugged onto the end of the other for the 45 purpose of extending a circuit and providing additional branches therefrom.

Figure 2 is an end view of one of the plug members.

Figures 3 and 4 are vertical or longitudinal sectional views of two of the units in 50 assembled relation, these views being taken on substantially the planes of lines 3—3 and 4—4 respectively of Figure 2.

In Figure 1 I have indicated at 5 the face

of a baseboard, wall or other outlet fixture 55 having a pair of the usual contact clips 6 for engagement by the blades of an ordinary attachment plug. I have also indicated in this view one of my special attachment plugs at 7 ready for engagement with the outlet fixture, a second attachment plug at 8 ready to be plugged into the first attachment plug and an end attachment plug at 9 ready to be coupled to the second plug. Each one of these plugs consists of an insulating base 10 having a pair of terminal blades 11 mounted on and projecting from one end of the same, the blades of these several plugs being interchangeably engageable with the contacts 6 on the outlet fixture, and provided at their 70 bases with suitable binding posts 12 for the circuit extension cords.

The through-circuit plugs, such as those indicated at 7 and 8 in Figure 1, are provided with contacts accessible at the ends 75 opposite the projecting blades for engagement by the blades of successively applied plugs. These circuit-extending contacts are shown at 13 in Figures 3 and 4 as housed in insulating sockets 14 in the lower or outer 80 ends of the plug bases, which sockets, for simplicity of manufacture, may extend entirely through the bases from end to end thereof, substantially as illustrated.

The through-circuit plugs (7 and 8) are 85 provided with cord outlets in the form of passages 15 extending entirely through the base of each plug from the binding posts at the upper end thereof, out through the bottom thereof so that in each instance the cord 90 or extension circuit conductor 16 emerges from the bottom of the plug to which it is attached. Clearance for this emerging portion of the cord is provided at the meeting ends of abutting plugs by means of notches 95 or recesses 17 formed in the upper edge portions of the plugs in position to line up with the cord outlets in the ends of preceding plugs.

The longitudinal cord passages 15 extending as they do substantially at right angles to the bases of the terminal blades, make a sharp turn for the cords at the binding posts and hence provide an efficient form of strain relief, and this strain relief may be 105 made more effective by providing an enlargement in the upper end of the cord outlet passage, such as I have indicated at 18, to

receive a knot tied in the conductor cord, as shown at 19 in Figure 3.

With this improved construction it will be seen that the cord is led off from the plug structure at an easy or gradual incline and that, as shown in Figure 3, the bent or angular part of the conductor is housed and protected from chafing, etc. Also it will be evident that by reason of the fact that the cord emerges directly from the end of the plug, it is effective to apply an endwise pull to the plug and this makes it possible for the units to be separated by simply pulling endwise on any one of the cords. This, therefore, provides an easy means for quickly uncoupling the plugs in case of a sudden necessity and also affords a certain amount of protection for the cords so that in case of a heavy strain on the cords, the plugs will be pulled apart before the cords will break. This overcomes to a large extent the dangers arising from short-circuiting, which otherwise might result from application of excessive force to the extension cords.

25 What I claim is:

1. In electrical apparatus of the character described, an attachment plug for extending a through circuit and providing a branch circuit comprising a cylindrical insulating base, a pair of terminal blades projecting from one end of said base and provided with binding posts at the bases of the same for the connection of a branch circuit, said insulating base having insulating sockets in the opposite end thereof and a cord outlet within the cylindrical outline of the base, extending from the binding posts at one end of the base out through the opposite end of the base closely adjacent to the insulating sockets at said opposite end of the base and terminal posts housed in the insulating sockets and electrically connected with the projecting terminal blades.

2. In electrical apparatus of the character described, an attachment plug for extending a through circuit and providing a branch circuit comprising a cylindrical insulating base having at one end a pair of connecting-in contacts and seated in the opposite end a pair of through-circuit terminals electrically

connected with the connecting-in contacts, said connecting-in contacts having binding posts and the insulating supporting base having a cord outlet within the cylindrical outline of the base near the edge thereof extending longitudinally therethrough from said binding posts at one end of the base out through the opposite end of the base and a notch in the edge at a point substantially opposite the cord outlet to accommodate the outgoing portion of a branch circuit cord from a preceding plug unit.

3. In electrical apparatus of the character described, a plurality of separable and interchangeably engageable circuit extension units, each comprising an insulating base having at one end a pair of connecting-in contacts and seated in the opposite end a pair of through-circuit terminals electrically connected with the connecting-in contacts, said connecting-in contacts having binding posts and the insulating supporting base having a cord outlet extending longitudinally therethrough from said binding posts at one end of the base to the opposite end of the base and a notch in the edge thereof positioned to accommodate the out-going portion of the extension cord from a preceding unit.

4. In electrical apparatus of the character described, a plurality of separable circuit extension units each comprising an insulating base and a pair of projecting terminal blades at one end of the same, one of said insulating bases having insulating sockets in the end thereof opposite the end from which the terminal blades project, terminal posts housed in said sockets and connected with the terminal blades and positioned to be engaged by the projecting blades of a succeeding unit, binding posts for the terminal blades on the first unit, the base of said first unit having a cord outlet extending from said binding posts out through the opposite end of the base and the base of the second unit having a notch in the edge thereof in line with the cord outlet opening in the end of the first unit.

In witness whereof, I have hereunto set my hand this 27th day of May, 1921.

DAVID CONLAN, JR.
